THERAPEUTIC COMPOSITION

Charles C. Johnson, New York, N. Y., assignor to
Latimer Laboratory, Inc., New York, N. Y., a
corporation of New York

No Drawing. Application February 3, 1942,
Serial No. 429,371

1 Claim. (Cl. 167—65)

The present invention is concerned with compositions of the type that function by the release of nascent oxygen under body heat for sustained therapeutic action.

As conducive to a clear understanding of the invention, it is noted that while the maximum available oxygen content of ozonized olive oil for practical purposes, is but 1.3 per cent, yet it is not feasible to use that composition full strength on delicate tissues. Such composition will cause a severe and painful stinging sensation when applied to the nasal passages for instance, unless the oxygen content is maintained at or below .5 per cent, i. e., not more than one-third full strength. Moreover, the completely ozonized olive oil has objectionable odors that are not easy to mask, and the attempt to mask the same leads to other difficulties.

Such ozonized oil is furthermore relatively immiscible with other oils such as unozonezed olive oil or mineral oil, so that dilution of full strength ozonized oil gives rise to mechanical difficulties, aside from the reduced therapeutic effectiveness of the diluted product. The introduction of foreign material such as solubilizing agents, in an effort to promote the mixture of the ozonized oil with diluent is apt to lead to other complications. On the other hand, where it is attempted to ozonize the olive oil to a lesser degree, within the limits that admit of painless application to delicate tissues the critical control of such limited addition of oxygen to the molecule is difficult and the stability of the product on storage is relatively low.

It is among the objects of the present invention to provide a composition with an oxygen content capable of being slowly released in nascent form under body heat, which oxygen content shall be much higher than the maximum attainable with olive oil, and which composition shall yet be non-irritating in its full concentration, even when applied to the most delicate tissues of the human body such, for instance, as the nasal passages.

Another object is to provide a composition for the above purpose, which is sufficiently viscous to stay in place for effective action on the organ or upon the tissue to which it is applied, which has no objectionable odor, and which, while it effectively releases nascent oxygen when applied to body tissues, will retain its effectiveness for all practical purposes, when sealed in a jar or flask in storage at normal room temperature for a period as much as two years.

According to the invention, in one practical

embodiment, substantially pure glycerine trioleate is ozonized by any of the conventional ozonizing processes, desirably by silent electric discharge. The double bond of each of the three acid radicals which esterify the glycerol is thus ozonized, three oxygen atoms bridging between the carbon atoms that flank the double bond on each of the three acid radicals.

The compound, when ozonized to the maximum extent practically attainable on a commercial scale, may contain as high as 1.85 per cent of available oxygen thus added to the molecule of glycerol trioleate, and this is fully fifty per cent higher than the corresponding maximum i. e. 1.3 per cent of oxygen capable of being combined with olive oil.

The effectiveness of the composition is thus considerably greater than that of ozonized olive oil, apart from the vitally important circumstance that it is non-irritating to delicate tissues such as those of the nasal passages even when used full strength. By reason of its high added oxygen content, the composition of the present invention is considerably more viscous than is correspondingly ozonized olive oil, so that it will more reliably remain in situ on the organ or on the tissues to which it is applied, without readily flowing therefrom and will function for hours by the slow release of therapeutic nascent oxygen given up by the molecule under body heat. The composition has no objectionable odor and need therefore not be masked and the mechanical difficulty of admixing essential oils therewith and the dilution and other objections incurred by such masking are obviated.

Except for the desired release of nascent oxygen there is no break-down of the molecular structure of the composition during use. No foreign matter such as ketones, aldehydes or the like, even small proportions of which would be irritating is present or is formed in the course of the use of the composition.

While the presence of such stable saturated oils in the composition as may be miscible with the ozonized glycerine trioleate would theoretically do no particular harm physiologically, dilution would be incurred, so that the available nascent oxygen is of lower percentage and the composition is accordingly less effective, without countervailing advantages, since as above noted, the ozonized glycerol trioleate even with its high available nascent oxygen content is non-irritating to delicate tissues.

The relatively viscous composition constituting the medicament of the present invention will

not deteriorate materially when stored in flasks or jars at normal room temperatures.

The composition is germicidal, fungicidal and deodorizing and is valuable for a wide variety of therapeutic uses, generally for external application. It is fatal to anaerobic organisms particularly, and destroys them effectively when the composition is applied to tissues, such as the nasal and vaginal tracts, the sinuses and the like. The composition produces exceptionally meritorious results in the treatment of secondary or tertiary burns. Another application is as a vermifuge. The composition may be solidified sufficiently to serve as an ointment or for suppository purposes, by admixing the same with hydrogenated cotton seed oil or the like.

Esters of fatty acids with two double bonds, such as linoleic acid, are in general unsuitable either as such, or as constituents of the composition, because in the release of oxygen they appear to break down into ketones, aldehydes and the like, that render the material irritating. Esters of acids with three double bonds such as linolenic acid are apparently even more objectionable from this standpoint. The ozonization of oils that contain such ingredients even in small proportions, especially if they also contain oxidizable coloring and flavoring matter is not

only wasteful of ozone, but yields a product of irritating and odoriferous character. Hydroxy acids with double bonds, such as ricinoleic acids and the esters thereof are in general objectionable because of their bad odor, among other reasons. Fatty acids as distinguished from the esters thereof are in general found to be too unstable for the purposes of this invention and in fact some of them tend to explode on ozonizing.

10 As many changes could be made in the above composition, and many apparently widely different embodiments of this invention could be made without departing from the scope of the claim, it is intended that all matter contained in the 15 above description shall be interpreted as illustrative and not in a limiting sense.

Having thus described my invention, what I claim as new and desire to secure by Letters Patent is:

20 A therapeutic composition consisting essentially of glycerol esterified with oleic acid and ozonized at the double bond of said acid to such extent as to have about 1.85 per cent of the total mass available as nascent oxygen releasable 25 therefrom under body heat, the composition after such release remaining substantially stable without polymerization, oxidation or decomposition.

CHARLES C. JOHNSON.
